UNITED STATES PATENT OFFICE

VICTOR C. ARMSTRONG, OF HACKENSACK, NEW JERSEY, ASSIGNOR TO THE RAIL JOINT COMPANY, OF NEW YORK, N. Y., A CORPORATION OF NEW YORK

RAIL-JOINT BAR

Application filed March 8, 1930. Serial No. 434,328.

This invention relates to rail joint bars, especially of the so-called "headfree" type, and has in view to provide certain improvements in such bars particularly designed to enable adjustments thereof to compensate for wear, and, in general, to increase the life and the efficiency of rail joints effected by means thereof.

As is understood in the art, the term "head-free" as applied to a rail joint bar is employed to designate a bar which takes loading engagement with the head fillet of the rail and has clearance from the underside of the rail head. Generally such bars are formed for base fishing contact with the upper face of the rail flange and for clearance between the heel of the bar and the web of the rail, whereby the base portion of the bar is adapted for inward adjustment and consequent wedging action against the upwardly and inwardly inclined upper face of the rail flange to elevate the bar and the rail ends so that the latter may be maintained high.

The standardized conventional headfree rail joint bar has continuous contact throughout its length, both at the head and at the base thereof, with the rails, so that when the bar is drawn into engagement with the rails the resulting joint is possessed of the requisite strength and rigidity. Moreover, in the headfree joint no appreciable wear takes place upon the head of the joint bar nor upon the head fillet of the rail, but wear is confined mostly to the base of the bar and to the upper face of the rail flange. Even this wear is more or less localized medially of the bar for a comparatively short distance extending outward from the ends of the rails, where the joint sustains practically all of the load forces imposed therein. Accordingly, continuous contact of a headfree bar throughout its length with the rails may beneficially be modified in some instances, by making such contact limited to the central area or medial zone of the joint, for example, according to the present invention.

In the drawings, wherein like characters of reference denote corresponding parts in the different views:—

Figure 1 is a side elevation, partly in sec-

tion, of a rail joint illustrating the use of the present joint bar.

Figure 2 is a vertical cross section taken approximately on the line 2—2 of Fig. 1;

Figure 3 is a vertical cross section taken approximately on the line 3—3 of Fig. 1; and

Figure 4 is a horizontal section taken approximately on the line 4—4 of Fig. 2.

Referring to the drawings in detail R, R' designate the meeting end portions of a pair of rails, and A a joint bar embodying the novel features of the present invention and adapted for splicing the rails R, R', together.

As usual, each rail is inclusive of a head 10, a web 11, a base or flange 12 and a head fillet 13 located at the point where the web 11 merges into the head 10.

The joint bar A, which is of "headfree" design, includes a head 14, a web 15 and a base or foot portion 16, and, being of a head-free design, the inner upper corner 14^a of the head 14 thereof is rounded for loading engagement with the head fillet 13 of the rail, and the top thereof is formed for clearance throughout the length of the bar from the under face of the rail head. Moreover, the base or foot portion 16 of the bar is formed for fishing contact with the upper face of the rail flange and the heel 16^a of the bar is formed for clearance from the rail web 11 whereby the bottom portion of the bar is adapted for inward adjustment to produce a wedging action between the bottom face of the bar and the upper face of the rail flange for the purpose of elevating the bar and the rail ends to maintain the latter high. This modified bar, however, is not constructed in accordance with prior practice to have loading engagement throughout its length with the rails R, R', but is to be constructed to have clearance at its ends, both at its head and at its base, from the rails whereby the latter are engaged by the bar only throughout that medial portion of the length of the bar which is load sustaining and subjected to the greatest wear. That is to say, a medial portion of the head 14 of the present joint bar, for a suitable distance extending from the center towards either end thereof, has its upper inner corner rounded as heretofore stated for

loading engagement with the head fillet of the rail, but from the ends of said medial portion to the ends of the bar said corner is stepped outwardly, as indicated at 17, to provide a clearance space 18 at each end of the bar between the upper inner corner of the head thereof and the head fillets 13, 13 of the rails, respectively. Similarly, a medial portion of the base 16 of the bar, preferably corresponding in length to the length of the aforesaid medial portion of the head of the bar, has its lower face formed for fishing contact with the upper faces of the rail flanges, but from the ends of said medial portion to the ends of the bar the said lower face of the base is stepped upwardly, as indicated at 19, to provide a clearance space 20 at each end of the bar between the under face of the base thereof and the upper faces of the rail flanges, respectively.

Thus, in the assembly of the present bar with the rails, only a medial portion of the bar, substantially corresponding in length to that portion of the bar which is subjected to maximum wear, takes loading engagement with the rails, the end portions of the bar, outwardly of said medial portion, having clearance from the rails. Accordingly, as wear occurs medially of the bar, the latter is capable of being drawn inward by the joint bolts 20 to compensate for the wear, and in this connection it is pointed out that by sufficiently tightening the outer joint bolts 20 the ends of the bar may be flexed inward whereby the constant and inherent tendency of the bar to assume a normal condition will result in an automatic inward wear compensating movement of the medial portion of the bar. Moreover, by reason of the clearance between the end portions of the bar and the rails, the joint is rendered flexible to a considerable extent and the wave motion of the rails is permitted to pass substantially uninterruptedly through the joint, with consequent substantial avoidance of pounding of the rail ends.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:-

1. A rail joint including the rails, the joint bolts and a joint bar having head and foot portions formed for loading engagement throughout the medial portion of the joint only, respectively with the head fillets of the rails and with the base flanges of the rails, and means responsive to the bolting pressure for causing an automatic rotation of the bar

to adapt the same to loading forces and to wear.

2. A rail joint including the rails, the joint bolts and a joint bar having clearance along its end portions from all parts of the rails and having head and foot portions formed, throughout the medial part of the bar only with bearing portions which respectively have loading engagement with the head fillets of the rails and with the base flanges of the rails, and means responsive to the bolting pressure for causing an automatic rotation of the bar to adapt the same to loading forces and to wear.

In testimony whereof I hereunto affix my signature:

VICTOR C. ARMSTRONG.
